UNITED STATES PATENT OFFICE.

PRATT C. MORRIS, OF THOMASVILLE, GEORGIA, ASSIGNOR TO CHARLES WHEELER COOPER, OF THOMASVILLE, GEORGIA.

COIL-BOX PROTECTOR.

1,338,581.

Specification of Letters Patent. Patented Apr. 27, 1920.

Original application filed May 16, 1918, Serial No. 234,978. Divided and this application filed October 6, 1919. Serial No. 328,676.

To all whom it may concern:

Be it known that I, PRATT C. MORRIS, a citizen of the United States, residing at Thomasville, in the county of Thomas and State of Georgia, have invented certain new and useful Improvements in Coil-Box Protectors; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to a protector for a coil box, more particularly of automobiles.

It has for its object to provide means for keeping the coil box dry or free from wet or dampness resulting from exposure to weather conditions or washing the vehicle or automobile. The coil box, especially in the Ford type of car, is attached to or supported from the dash-board of the car, which being exposed becomes wet or damp from exposure in wet weather and also in washing the car, and this moisture being communicated to the coils of the box frequently causes a short circuit and for the time being puts the car out of commission. With the view of protecting the coil box and preventing the short circuiting mentioned, the invention consists in the features hereinafter described and then sought to be clearly defined by the claims reference being had to the accompanying drawing forming a part hereof, and in which—

Figure 1 is a side view of the forward portion of an automobile of the Ford type, with a portion broken away and showing the dash-board and the protector in vertical section;

Fig. 2 is a front view of the protector or shield;

Fig. 3 a vertical section through the protector on the line 3—3 of Fig. 2, looking in the direction of the arrows;

Fig. 4 is a view similar to Fig. 3, showing an insulating lining, for instance rubber, to the nipples.

In the drawing the numeral 1 designates a portion of an automobile, for instance, the cowl, and 2 the dash-board in a car of the Ford type. 4 designates the coil-box cover

or case in which is contained the coil-box from which extend the porcelain covered terminals or binding posts 5 for connection therewith of the conductors 6, all as usual in cars of the type mentioned. The coil box protector or shield is designated by the numeral 7. It is made of sheet metal, or other suitable material, and preferably formed with forwardly projecting nipples or tubes 8, corresponding in number to the terminals or binding posts of the coil box, and extending through a corresponding number 65 of openings in the dash-board. The protector lies between the dash-board and the coil box as illustrated in Fig. 1 and will be bolted to the dash-board by bolts (not shown) passing through the dash-board and holes 9 made in the protector, or otherwise secured in place, and the terminals or binding posts of the coil-box will pass through the nipples 8 of the protector and have the conductors connected thereto as shown in Fig. 1. The upper end 10 of the protector is curved or deflected backwardly above the top or cover to the coil-box as illustrated in Fig. 1 so that any water entering through the automobile front portion or between the cowl and dash-board, at the top of the dash-board will be caught by the curved or overhanging top of the protector and directed down the front face of the protector away from the coil-box, thereby protecting the face of the box from water and moisture and preventing short-circuiting and weakening of the spark. The protector formed and applied as described effectively shields the coil box and its terminals from water that may enter about the dash-board and also against the dampness or moisture that might be absorbed by the wooden face of the box, or trickle down the dash-board, and thus the short circuiting heretofore occurring in coil boxes of automobiles is prevented.

If desired, the nipples 8 may be lined with an insulating material such as rubber, which may be soft rubber, and while this might in some cases be desirable it is not absolutely necessary. While the nipples tend to protect the terminals, yet the coil box is protected by the shield which directs water away from the face of the box and thus protects the box against absorbing moisture.

and against water that might otherwise trickle down the face of the box and cause short circuiting.

This is filed as a division of my application filed May 16, 1918, Serial 234,978.

I have described the preferred construction of the protector but changes in details may be made and essentials of the invention retained.

16 Having described my invention and set forth its merits, what I claim is:

1. A protector for coil-boxes of motor vehicles, comprising a member adapted to fit between the coil-box and dash-board of

15 the vehicle and formed with nipples to fit in openings in the dash-board and receive the terminals or binding posts of the coil-box and having its upper end extended rearwardly to lie above the coil-box.

20 2. A protector for coil-boxes of motor vehicles, comprising a member having a body portion formed to fit between the coil-box and a dash-board of the vehicle and about the terminals or binding posts of the 25 coil box and provided at its upper end with a deflector to extend over the coil-box adjacent to the binding-post face of the box.

3. The combination with a coil-box, cowl, and dash-board of a motor-vehicle, of a protector applied to the face of the coil-box from which its terminals or binding posts

project between the box and dash-board and provided with a deflector extended to lie above and over the coil-box between it and the cowl.

4. The combination with a coil-box, cowl, and dash-board of a motor vehicle, of a protector for the box comprising a member applied to lie between the dash-board and coil-box and having a deflector disposed to 40 lie over the coil-box between it and the cowl at the face of the box from which its terminals or binding posts project, said protector serving to protect the terminal or binding-post face of the box against short circuiting from moisture.

5. A protector for coil-boxes of motor vehicles, comprising a member having a body portion formed to fit between the coil-box and a dash-board and provided at its 50 upper end with a deflector to extend over the coil-box adjacent to the face of the box from which its terminals or binding posts project, said body portion being provided with projecting terminal-shields having an insulating lining.

In testimony whereof I affix my signature in presence of two witnesses.

PRATT C. MORRIS.
